UNITED STATES PATENT OFFICE.

SAMUEL S. STOLP, OF LOUISVILLE, KENTUCKY.

ELECTRICALLY-OPERATED TRACK SWITCH.

Application filed September 23, 1925. Serial No. 58,036.

To all whom it may concern:

Be it known that I, SAMUEL S. STOLP, a citizen of the United States of America, residing at Louisville, in the county of Jefferson and State of Kentucky, have invented certain new and useful Improvements in Electrically-Operated Track Switches, of which the following is a specification.

My invention relates to electrical systems and particularly to that class of systems adapted to automatically position the track switch from a moving vehicle so that the vehicle will be switched in a predetermined direction at the will of the operator of the vehicle. This application is a continuation, in part, of my copending application Serial No. 672,745, filed November 5, 1923.

One object of my invention is to produce a system as simple as possible to selectively operate the track switch.

Another object of my invention is to prevent the application of current to certain operating parts beyond a predetermined time so as to avoid injury to such parts, as by the burning out of said parts.

Another object of my invention is to permit of the application of the operating current to certain parts for a sufficient time to operate the same, as for instance, a sufficient time to fully saturate certain solenoids or other electrical means, as for instance, an electric motor, which moves the track switch.

Still another object of my invention is to prevent operation of the switch, after a predetermined time, by the vehicle first operating it, that is, after the device has been operated to the proper position and after the saturation of certain parts has been accomplished.

Still another object of my invention is to allow a plurality of vehicles to pass a predetermined point without changing the position of the switch from that set by the leading vehicle and before the leading vehicle has passed the switch.

The system is so arranged that it may be operated by the motorman when he reaches a certain predetermined point by placing his controller in either an "on" or an "off" position, depending upon the direction in which he wishes to operate the track switch. In a device of this class it is usual to so arrange the operating parts that the track switch will be moved into a straight position if the car passes the predetermined point with the

controller in the "off" position, or, as it is usually stated, in the "power off" position. If the vehicle passes the predetermined point with the controller in the "on" position, that is, "power on" the track switch will be positioned to carry the vehicle around a curve. The predetermined point referred to is that point where an overhead contactor or contact pan is positioned in advance of the track switch and which is engaged by the current collector on the vehicle.

Further objects and advantages of my invention will disclose themselves to those skilled in the art as the further description of my invention proceeds, and when read in conjunction with the drawings accompanying this specification.

In the accompanying drawings:

Fig. 1 is a diagrammatic view showing those parts and circuits only of an electrically operated vehicle which affect the track throwing system herein described, or by means of which the track throwing system may be operated.

Fig. 2 shows the relation of the current collector to the overhead contact pan or device and to the trolley wire as the current collector of the moving vehicle passes the contact pan.

In Fig. 3 I have shown a diagrammatic arrangement of various parts and circuits which compose my invention, but does not show the detailed construction of the various parts as such construction may be quite varied and still operate in the system successfully.

In the system which I have disclosed in Fig. 3, I employ a contact pan P provided with two parallel contact members 1 and 2 which are spaced apart and normally insulated from each other. The contact pan is mounted upon the trolley wire 3 with the members 1 and 2 spaced therefrom. The members 1 and 2 are so positioned with respect to the trolley wire 3, which is usually continuous, as indicated by the dotted line, that they are insulated from the trolley wire and will prevent the engagement of the current collector W from engaging with the trolley wire 3 while the current collector is in engagement with the members 1 and 2 (see Fig. 2). The construction and arrangement of the contact pan P' is the same or similar to that of the contact pan P.

Connected to the trolley wire and to the

contact member 2 is a coil 4 of an electrically operated switch S. The winding on this coil is so proportioned that the switch member 5 will not be operated by the coil 4 unless the vehicle passes the contact pan P with "power on."

Referring to Fig. 1, when the current collector W on a moving vehicle engages the members 1 and 2 these members are short circuited or electrically connected and there are several possible sources of flow of current from the members 1 and 2 through the vehicle to the ground, as for instance, one is through the heater elements H, another is through the light circuit L, another is through the air compressor circuit A, another is through the operating motor M under the control of the motorman through the medium of the controller C. At certain times the elements H, L and A are always in circuit between the current collector W and the ground G and the current will then be flowing through these elements, and as they are usually in parallel the current supplying them is accumulative and may be of considerable value. The current flowing through the motor M is always under control of the motorman through the medium of the controller C, that is, he is always in a position to permit or prevent at will current flowing through the motor M which operates the vehicle. This current is usually of very high value as compared with the current which may flow through the elements H, L, A, etc.

In designing the winding of the coil 4, the fact must be taken into consideration that there may be at all times current flowing through the elements H, L and A and, therefore, the winding 4 must be so designed that the switch-arm 5 will not be operated by the energizing of the coil 4 except when the motorman applies current to the motor M. It will be noted that there is one or more paths by which the current from the trolley wire may flow to ground by way of the vehicle. If now the current collector W engages the members 1 and 2 and the circuits are complete through the members H, L and A, but the controller C is in the "power off" position, current will then flow from the trolley wire 3 through the conductors 6 and 7, the coil 4, the conductors 8 and 9, the member 2, the collector W, trolley pole T and members H, L and A to the ground G.

Should the coil 4 not be wound properly the current flowing would cause the switch-arm 5 to be raised, which is not desired with "power off" operation. If, while the collector W is engaging the members 1 and 2 and the members H, L and A are switched off and the motorman should operate his controller to the "power on" position, current would then flow from the trolley wire

3 through the elements 6, 7, 4, 8, 9, 2, W, T, C and M to ground. If the coil 4 is properly designed this current will be sufficient to operate the switch-arm 5, a condition, which is desired, with "power on" operation. From this it will be seen that the switch-arm 5 is operated only when the controller C is in the "power on" position. When the collector W engages the members 1 and 2 these members will be short circuited or electrically connected by the collector W and the member 1 will then be connected to the trolley wire through the elements W, 2, 9, 8, 4, 7 and 6.

To operate the switch-tongue 10 I employ two solenoids 11 and 22, each having one terminal connected to the ground G and the other terminal connected to one of the contacts 13 and 14 of the selector switch S. The solenoid 12 is connected to the contact 13 by the conductor 15 and the solenoid 11 is connected to the contact 14 through the conductors 16 and 17 and the normally closed switch-arm 18. The solenoids 11 and 12 are provided with a common reciprocating plunger 49 which in turn is connected by proper mechanism to the switch-tongue 10 and constitutes a reciprocating motor so that when the solenoid 11 is energized the tongue 10 will be thrown to the straight ahead position, as shown in the drawing, and when the solenoid 12 is energized the switch tongue will be thrown to the curve position, as shown by the dotted lines.

The switch-arm 5 is connected to the member 1 by means of the conductor 20 and is normally in engagement with the contact 14 which is connected to the coil 11. Therefore, whenever the member 1 is energized by the short circuiting of the members 1 and 2 by the collector W and the motorman simultaneously moves his controller C to the "power off" position, the coil 11 will be energized and move the switch-tongue to the straight ahead position. In order to maintain the switch-arm 18 in a normally closed relation with the contact 21 between periods of operation by moving vehicles, I employ an operating magnet B which is provided with a core and with two coils 40 and 41. One terminal of the coil 40 is connected to the conductor 7 by means of the conductor 42 and the other end of the coil 40 is connected to the ground through the conductors 43, 5, 14, 17, 21, 18, 16, 11 and 27.

It will be seen that the coil 40 is normally connected between the trolley wire and the ground G and the current will flow therethrough at all times that the switch 18 engages the contact 21 and will maintain the switch-arm 18 normally in engagement with the contact 21. The coil 41 is connected to the contact 44 of the pan P' through the conductor 47 and to the ground through the conductors 48, 16, 11 and 27, and it will be

noted that unless the members 44 and 45 are connected together, as for instance, by the moving current collector W, that no current will flow through the coil 41 and, therefore, the coil 41 will have no influence upon the switch-arm 18 unless the contacts 44 and 45 are connected.

It will be noted that when the system is in its normally set position for operation

10 that one terminal of the coil 40 is connected to the contact 1 through the elements 43 and 20 and the other terminal is connected to the contact 2 through the elements 42, 7, 4, 8 and 9, and that whenever the current

15 collector W engages the contacts 1 and 2 that the terminals of the coil 40 will be short circuited as the resistance of the coil 40 is quite high so as to permit only a very small current to flow therethrough and the

20 resistance of the coil 4 is very low. Therefore, whenever a vehicle passes the pan and the collector W engages the contacts 1 and 2 of the pan P and the controller is in the "power on" or "power off" position that the

25 coil 40 will be short circuited and hence the switch B will be de-energized and the switch-arm 18 opens and will drop out of engagement with the contact 21, but the conducting member 30 of the switch-arm 18 will

30 engage and electrically connect the contacts 32 and 33 and the system is rendered inoperative as to further change to the switch tongue either by the first vehicle or by a vehicle following. The switch B will re-

35 main open with relation to the contact 21 during the time that the collector engages the pan P, but it will not drop out of engagement with the contact 21 for a predetermined time after the collector engages the

40 pan for the reason that the switch B is provided with a time element or lag thereby preventing the opening of the switch B for a time after the collector engages the pan P, and hence if the engagement is with the

45 controller set at "power off" the current will flow from the conductor 3 through the elements 6, 7, 4, 8, 9, 2, W, 1, 20, 5, 14, 17, 21, 18, 16, 11 and 27 to ground and the switch-tongue 10 will be operated to the

50 straight ahead position if it is set to the curve position, but this current ceases to flow as soon as the switch-arm 18 drops. Lag in the operation of the switch B may be secured by the use of the heavy copper

55 collar 29 as is well known to those skilled in the art.

If the collector engages the pan P with "power on" current will flow from the conductor 3 through the elements 6, 7, 4, 8, 9, W, C and M to ground and in this case the coil 4 will be energized, the arm 5 moved into engagement with the contact 13 and then current will flow from the conductor 3 through the elements 6, 7, 4, 8, 9, W, 1, 20, 5, 13, 15, 12 and 27 to ground thereby

energizing the coil 12 and moving the switch tongue 10 to its curved position. The short circuiting of the elements 1 and 2 of the pan P by the collector W will short circuit the coil 40 as already explained, and the contact arm 18 will drop out of engagement with the contact 21 and into engagement with the contacts 32 and 33.

Whenever the conducting member 30 of the arm 18, and which are insulated from each other, engages with the contacts 32 and 33 thereby connecting them, a short circuit is placed across the coil 4 through the medium of the conductors 34 and 35 connected to the contacts 32 and 33 respectively. From this it will be seen that when the arm 18 has dropped either from the current collector W engaging the pan P with "power on" or "power off" that the operation thereafter of the switch tongue 10 cannot take place until the arm 18 has been placed in its normal position in contact with the member 21 for the reason that when the arm 18 has dropped the circuit leading to the coil 11 has been opened at 21 and the coil 4 has been short circuited at the contacts 32 and 33 thereby making it impossible to energize the coil 4 to pick up the arm 5 and the circuit leading to the coil 12 will remain open, therefore, it will be apparent that a vehicle having once positioned the switch 10 by passing the pan P with "power on" or "power off" that a car following immediately cannot change the setting of the switch tongue 10.

In order to reset the system to normal so that it is possible for a car following the first car to operate the switch I provide the second pan P' positioned at a point sufficiently beyond the switch tongue 10 such that the vehicle will have passed the switch tongue 10 before its collector will engage the pan P' after which it makes no difference how soon the following car may pass the pan P.

Through the medium of the pan P' I provide means for resetting the switch B to normal which comprises the coil 41 with its leads 47 and 48 and the connection 46 between the trolley conductor 3 and the contact 45. It will be evident that when a collector engages the pan P' that current will flow from the conductor 3 through the elements 46, 45, W, 44, 47, 41, 48, 16, 11 and 27 to ground thereby energizing the coil 41, then causing it to pick up the arm 18 and into engagement with the contact 21 thereby re-establishing the flow of current through the coil 40. As soon as the collector W leaves the pan P' the coil 41 will be de-energized, but the coil 40 will remain energized and holding the arm 18 in normal position in engagement with the contact 21 and the system will be ready for operation by a car following.

The winding of the coils 40 and 41 is sufficiently high in ohmic resistance to allow only a small current to flow therethrough which is not sufficient to energize the coils 5 4, 11 and 12 to an operating degree.

The switches S and B are usually mounted in a box upon the pole adjacent to the track switch operating means which is located in the ground adjacent the switch tongue 10 10 and connections lead out from the box to the trolley wire or pans and to the track switch.

If the speed of the vehicle is slow enough and the length of the switch pan P is great enough such that the arm 18 will drop before the vehicle has passed the pan and the motorman crosses the pan with "power on" 15 the switch arm will first open the circuit to the coil 11 and then short circuit the coil 4 and force the arm 5 to drop, but the track switch tongue will not be changed from the curved position.

If the motorman should intend to cross the pan P with current off, but should come to rest with its collector engaging the pan P, 20 it is quite evident that unless there is some means of rendering the coil 4 inoperative that when the motorman starts his car a heavy rush of current would energize the coil 4 picking up the arm 5 and setting the switch tongue 10 to the wrong position, but this difficulty is overcome by the short circuiting action of the contact 30 when it engages the contacts 32 and 33 which it does 25 after the collector has engaged the pan for a predetermined length of time sufficient to assure the energizing of the coil 11. The opening of the arm 18 under such conditions also avoids the continued flow of current 30 through the coil 11 and, therefore, it is possible to wind the coil 11 with a higher degree 35 of saturation without the fear of its being burned out from prolonged application of the current.

There is a remote possibility of the motorman coming to rest with the collector engaging the pan P if he first engages it with the intention to take the curve, as he will 40 then engage the pan with "power on" and he is not likely to stop with the collector in contact with the pan. However, should this occur, the arm 18 will drop after the predetermined time has elapsed, the relay opening the circuit to the solenoid coil 11 and short circuiting the coil 4, hence forcing the arm 5 to drop so that further operation of the switch tongue will be prevented while the collector engages the pan P.

There are, of course, modifications which may be made from the disclosure herein given which will still be within the scope of my invention, as for instance, a rotary motor may be employed to operate the tongue 10 in place of the reciprocating motor shown, and other changes will suggest themselves 55 to those skilled in the art.

I claim:

1. In a switch operating system, the combination of an electrically operated switch throwing device and circuits thereto, an electrically operated selector switch therein to control the flow of current through different parts of the switch throwing device, an electrically operated switch to open and close one of the circuits when the system is in use so that a current collector will first open said electrically operated switch and short circuit the selector switch and will later close the electrically operated switch whereby the system will be rendered inoperative during the opening and closing 75 of said switch.

2. In a switch operating system, the combination of an electrically operated switch throwing device, two contact pans to be engaged by a current collector and circuits leading thereto, an electrically operated selector switch for controlling the flow of current through different parts of the switch throwing device, electrically operated means for opening and closing one of the circuits 80 to the switch throwing device when the system is in use, circuits leading to the electrically operated means such that the collector will first open said means and short circuit the selector switch after a predetermined time the collector engages one pan and close the said means when the collector engages the other pan.

3. In a switch operating system, the combination of an electrically operated track switch, a selector switch to direct current to different parts of the track switch, a contact pan to be engaged by a current collector, a divided circuit from the contact pan to the track switch with the selector switch 100 interposed in one part of the circuit, an electrically operated switch interposed in a part 105 of the circuit, connections from the pan to the electrically operated switch and arranged to open after a predetermined time 110 after the pan is engaged by the collector and short circuit the selector switch, a second pan to be engaged by the collector, connections to the second pan to the electrically operated switch to close the same 115 when the collector engages said second pan.

4. A switching mechanism comprising in combination, a trolley wire, a contact pan, an electrically operated switch throwing device operated at will of the operator on a moving car, a selector switch operated automatically by energizing its operating coil during the movement of the car for transmitting current from the trolley wire to the switch throwing device to operate the 120 device in the proper direction, means to render the selector switch inoperative by shunting its operating coil after a predetermined time to prevent transmitting current to the switch throwing device and means 125 130

to remove said shunt and return the system to normal after the car has moved a predetermined distance beyond the track switch.

5. A track switch operating mechanism comprising means controlled by the operator of a moving vehicle to move the switch to a desired position, shunting means beyond the control of the operator to shunt the first

said means to render the system inoperative 10 either by the operator of the vehicle or the operator of a following car and means operated by the first vehicle to remove the shunt and return the system to normal after it has passed a predetermined point. 15

In testimony whereof I affix my signature.

SAMUEL S. STOLP.
